UNITED STATES PATENT OFFICE.

FREDERICK W. WOLF, OF CHICAGO, ILLINOIS.

RAILWAY-SWITCH.

No. 800,529.

Specification of Letters Patent.

Patented Sept. 26, 1905.

Application filed January 14, 1905. Serial No. 241,025.

To all whom it may concern:

Be it known that I, FREDERICK W. WOLF, a citizen of the United States, residing at Chicago, in the county of Cook and State of Illinois, have invented new and useful Improvements in Railway-Switches, of which the following is a specification.

This invention is an improved railway-switch, automatic to the extent that it closes after the passage of a train onto the side track. It is characterized by improvements, as will more fully appear hereinafter.

In the accompanying drawings, Figure 1 is a plan view of the switch closed. Fig. 2 is a similar view, open. Fig. 3 is a cross-section on the line 3 3 of Fig. 1.

Referring specifically to the drawings, the main-track rails are indicated at 6, and the side-track rail at 7.

8 represents the switch-points, pivoted at 9, connected together by bars 10 and also by a plate 11. The points swing laterally to open and close the switch.

The switch-stand is indicated at 12 with its vertical lever 13 connected by drag-links 14 and 15 to a plate 16, located directly under the plate 11. The plate 11 is slidably superposed on the plate 16, said plates being secured together by headed pins 17, which extend through slots 18 to allow the relative sliding movement mentioned.

The plates 11 and 16 are respectively struck up and down to form a longitudinally-extending recess for the coiled spring 19. This spring bears at one end against the plate 11 and at the other end against a projecting lug 20 on the plate 16, and the pressure of the spring tends to extend or slide the plates lengthwise to the extent permitted by the pins 17 in the slots 18.

The respective plates 11 and 16 have notches 11^a and 16^a, which register at half-throw or quarter-turn of the switch-lever 13. The top plate 11 has secured thereto a pair of flat springs 21, which carry at their ends wedge-shaped lugs 22, properly positioned to enter the notches 11^a and 16^a and lock the plates 11 and 16 together, when the notches are caused to register. The springs 21 normally lift the lugs 22 out of the notches. Said lugs are caused to be engaged into the notches by means hereinafter described.

Extending along beside the inner edge of the tread of the outer rail 6 and the outer switch-point 8 are tripper-bars 23, carried by arms 24, extending from rock-shafts 25,

which are carried, respectively, in bearing-blocks 26, mounted on the road-bed in the case of the main track and in bearing-blocks 27, secured to the cross-bars 10, in the case 60 of the switch-point. The trippers 23 are arranged so that the wheel-flanges will ride thereon and depress the same when a train is passing. Each rock-shaft 25 has at the end an arm 28, arranged to bear upon the top of 65 the spring 21 and depress the same when a wheel-flange rides upon the tripper-bar. When either spring is depressed, the plates 11 and 16 are locked together, as above referred to.

The tripper-bars 23 are normally held in raised position by springs 29, which are secured to the under side of said bars and bear upon the flanges of the rail-base. These springs are of considerable strength, so that 75 the tripper-bars cannot be operated except under great weight, as of a railroad-car. The target 30 is operated by a crank connection to a rod 31, which is connected to the plate 11.

With respect to the operation it should be 80 premised that the arm of the lever 13, which is attached to the drag-link 14, is of such length that the switch will be opened by a quarter-turn thereof. In Fig. 1 the switch is shown closed. Since the plates 11 and 16 are 85 slidable with respect to each other except when locked by the lugs 22, it will be seen that the switch cannot be opened except when they are locked, because when not locked the plate 16 would simply slide back and forth on the under side of the plate 11 without moving the latter. To let a train from the main track onto the side track, the engine is brought to the position where its wheel-flanges depress the tripper 23, causing the arm 28 to bear on 90 top of the spring 21. The switch is then given a quarter-turn in the direction of the arrow shown in Fig. 1. This draws the plate 16 inwardly or toward the side track, and at the quarter-turn the plate 16 has moved to the 95 position where the lug 22, by reason of the pressure on the spring 21, snaps down into the notch 16^a. This locks the plates 11 and 16 together. The switch-lever 13 is then moved the remaining quarter-turn to make a 100 full half-turn. The effect of this is to push the plates 11 and 16 outwardly, which swings the switch-points 8 and opens the switch. As long as the wheel-flanges continue to press 105 down the tripper-bar 23 the switch will remain open. When the last car shall have passed off of the switch-bars 23, the springs

110

21 lift the lugs 22 from the notches 16^a, thus unlocking the plates. It will be understood that when the switch-lever 13 was given the first quarter - turn the spring 19 was com-
5 pressed by the movement of the plate 16 under the plate 11. When the cars shall have passed and the plates shall have been unlocked, as above stated, the spring acts and throws the plate 11, and with it the switch-points 8,
10 toward the side track, thereby automatically closing the switch and opening the main track.

When a train is leaving the side track for the main track, its wheel-flanges strike the points 8 and throw them over by force. The
15 spring 19 yields to allow this movement, and when the train shall have passed onto the main track the spring acts to restore the switch-points to the normally closed position.

It will be seen that the switch is safe from
20 ordinary tampering therewith, since it cannot be operated except the tripper-bars are depressed. The tripper-bars are so long that one or more car-wheels will always be upon either or both of them during the passage of
25 the train.

What I claim as new, and desire to secure by Letters Patent, is—

1. In a switch, in combination, a switch-point and lever normally disconnected, train-
30 actuated means extending along the track in both directions from the switch-point to connect them, and means to hold the switch-point in closed position when so disconnected.

2. In a switch, in combination, switch-points
35 and a lever normally disconnected, plates slide-
able upon each other between the switch-points and connected respectively to the switch-points and lever, train - actuated means extending along the track in both directions from the
40 switch-points to lock the plates together, so

that the switch may be opened by the lever, and means to swing the switch-points to closed position when the plates are unlocked.

3. In a switch, in combination, switch-points arranged to swing to contact with opposite 45 rails, a plate connecting said points and having notches, another plate slideable under said plate and connected to the switch-lever and having notches arranged to register with the said notches, springs secured to one of the 50 plates and carrying lugs, arranged to enter the notches and lock the plates together, tripper-bars extending along beside the rails, to be depressed by wheel-flanges, levers connected to the tripper-bars and having arms 55 which bear upon the springs and force the lugs into the notches when the bars are depressed, and a spring located between the said plates and acting to swing the points closed when the plates are unlocked.

4. In a switch, in combination, a switch-point and lever, superposed plates slideable upon each other, one of which is connected to the switch-point and the other of which is connected to the lever, and having notches 65 arranged to register when the latter plate is moved by the lever, a spring between the plates, tending to shift the plate connected to the switch-point to close the switch, yielding lugs carried by one of the plates, and train-
70 actuated means to force the lugs into the notches to lock the plates together when the notches are caused to register.

In testimony whereof I have signed my name to this specification in the presence of two sub- 75 scribing witnesses.

FREDERICK W. WOLF.
